ANTENNA CIRCUIT MODULATION

George H. Brown, Haddonfield, N. J., assignor to
Radio Corporation of America, a corporation
of Delaware

Application July 16, 1936, Serial No. 90,825

11 Claims. (Cl. 250—17)

My invention relates to modulation systems. More specifically my invention is a radio system in which the modulation of carrier currents is effected by radiating a carrier wave from one antenna and sideband waves from two or more antennas spaced from the carrier current antenna.

In a conventional modulation system, carrier currents and modulation currents are impressed on an amplifier or modulator stage or stages. If the modulation is complete, i. e. one hundred percent, the amplifier or modulator stage must be able to handle four times the carrier power. The provision for the peak modulation requires an amplifier power capacity which is far in excess of average requirements. This means low average operating efficiency. A power amplifier, of this type, is not only inefficient but relatively costly.

I propose to provide a modulation system in which the carrier currents are impressed on one antenna. The carrier currents will be amplified without being modulated. Since the carrier current amplifier may be operated continuously at its rated capacity, its efficiency will be high. The side bands, without carrier, may be fed to a plurality of separate antennas. The waves from the carrier antenna and the waves from sideband antennas will be propagated substantially as a conventional antenna system propagates a modulated carrier wave.

One of the objects of my invention is to provide a novel means of establishing a modulated wave in space.

Another object is to provide means for radiating an unmodulated carrier wave from one antenna and simultaneously radiating modulation waves from separated antennas to effect modulated carrier waves at points remote from the antennas.

Another object is to provide a plurality of means for radiating waves comprising: An unmodulated carrier, an upper side band, and a lower side band.

A still further object is to provide a system with means for radiating an unmodulated carrier wave from one antenna, and modulating said carrier at a remote receiver by radiating the modulation waves from a plurality of antennas spaced from the carrier antenna.

My invention may be best understood by reference to the accompanying drawings in which Figure 1 is a schematic diagram of one embodiment of my invention.

Fig. 2 is a schematic diagram illustrating a modification of my invention,

Fig. 3 is a graph showing the characteristic modulated field pattern of the system of Fig. 2,

Fig. 4 is a schematic diagram of a modification of the system of Fig. 2,

Fig. 5 is a graph showing the characteristic modulated field pattern of the system of Fig. 4, and,

Fig. 6 is a schematic diagram of the system of Fig. 1 applied to a short wave vertical antenna system.

In Fig. 1 a crystal oscillator 1 generates a current of frequency F . Currents of frequency F are fed through a buffer stage 3 to a balanced modulator 5. The modulating currents of frequency f_v are impressed through a microphone 7 or the like, on a speech amplifier 9. The amplified modulating currents of frequency f_v are impressed on the balanced modulator 5. The output of the balanced modulator supplies currents of frequency $F+f_v$ and $F-f_v$. The currents of these frequencies ($F+f_v$ and $F-f_v$) are separated by filters 11, 13.

The carrier frequency currents f_c , generated by the carrier crystal oscillator 15, are impressed through a carrier wave amplifier 16 and a transformer 17 or other coupling means, in an antenna 18 which radiates the unmodulated carrier wave of frequency f_c . Currents of frequency F and f_c , respectively, supplied by the crystal oscillator 1 and carrier crystal 15 are impressed on a modulator 19. This modulator establishes currents of frequency f_c+F and f_c-F . A suitable filter 21 attenuates the former frequency f_c+F and passes currents of the latter frequency f_c-F .

The last mentioned currents f_c-F and currents of frequency $F-f_v$ are impressed on a modulator 23. The output of this modulator includes currents of frequency f_c-f_v and other components which may be neglected. The currents of frequency f_c-f_v are one of the sidebands resulting from the difference between carrier frequency f_c and the modulation frequency f_v . These currents are fed through a transformer 25 to the antenna 27 from which waves of frequency f_c-f_v are radiated.

Currents of frequencies f_c-F and $F+f_v$ are impressed on a modulator 29. The output of modulator 29 includes currents of frequency f_c+f_v are radiated. Thus it will be seen that the foregoing arrangement establishes currents of three frequencies: carrier f_c , upper side band f_c+f_v and lower side band f_c-f_v .

If the antennas 18, 27 and 33 are widely spaced, so that there is no radiation coupling, it can be shown that a "space" modulated wave will be

propagated throughout the service area. The antennas are preferably arranged with the sideband radiators about two wave lengths apart and the carrier antenna 43 spaced equally distant from 5 the sideband antennas and on the line connecting these antennas 21, 33. The calculations of power are biased on the use of quarter wave antennas, unless otherwise specified. The invention may be practiced with antennas of any suitable dimensions.

If the radiators cannot be placed a wave length or more apart, the reactive component of the radiation coupling can be nullified by using a link circuit to induce voltages in phase opposition to the 15 reactive coupling voltages. The mutual resistance term can be made zero by spacing the antennas .45, .9, 1.5, 2.0, or 2.5 etc. wave lengths apart. Assuming that both couplings are zero, the carrier power represents 100 units, the average power 20 supplied by the transmitter for 100% modulation 150 units, and the peak power for 100% modulation 150 units. In contrast a conventional modulation system has carrier power 100 units, average power 150 units, and peak power of 400 units. 25 This indicates a very substantial saving in power, apparatus and maintenance, and a corresponding increase in efficiency in favor of the "space" modulated system. The foregoing improvement is due in part to the very high efficiency of the carrier wave amplifiers. The side band modulators or amplifiers operate at high efficiency on peak modulation, the amount of power being transmitted through the modulator-amplifiers is so small in comparison to the carrier power that the 30 low efficiency is not important.

Although the foregoing system represents a preferred form of my invention and produces a "space" modulated wave which has a uniform circular field, a more simple method may be employed at the expense of a less perfect "space" 40 modulation field. In Fig. 2 a system is shown in which currents representing side band frequencies $f_c + f_v$ and $f_c - f_v$ from source 35 are impressed in phase opposition on the antennas 31, 39. Currents of carrier frequency are impressed from a 45 suitable source 41 on the center or carrier frequency antenna 43.

In the system of Fig. 2 the carrier frequency currents f_c are separate from the currents of side band frequencies $f_c \pm f_v$. The antenna arrangement is adjusted so that the equal and oppositely phased currents in the sideband antennas induce 50 no voltages in the center or carrier current antenna. Likewise the center antenna induces no 55 carrier currents in the side band antenna circuits.

The system of Fig. 2 propagates waves of carrier frequency throughout a uniform circular field. The side band radiation follows a figure 8 pattern. While these fields produce a space modulated wave which may be received throughout most of the service area, the percentage modulation varies with respect to the angle between a line joining the antennas, and the line from the center antenna to the receiver.

If the antennas are spaced one quarter of a 60 wave length and θ is the angle between the line through the transmitting antennas and the line from the center antenna to the receiver, the modulation factor will be a maximum when $\theta=0^\circ$ and zero when $\theta=90^\circ$. The modulation factor has 65 been plotted against the angle in degrees in the graph X shown in Fig. 3. In the system of Fig. 2 the carrier power may be represented as 100 units, the average power supplied for 100% modulation 70 111.2 units, and the peak power supplied for 100% 75

modulation 141.8 units. These figures indicate a substantial improvement in efficiency over the conventional modulation system.

The system illustrated in Fig. 2 has a disadvantage in the variation of the percentage of modulation with the angle θ . This disadvantage may be minimized by employing a plurality of radiators of currents of side band frequency as shown in Fig. 4. In the arrangement of this antenna array, the unmodulated carrier currents from 10 source 45 are impressed on the antenna 47. The upper and lower side band current $f_c \pm f_v$ are impressed on the sideband antennas 49, 51, 53, 55, 57, 59. The distance d between the several antennas is .45 of a wave length. The modulation 15 factor is now represented in terms of the angle θ in the graph Y shown in Fig. 5. The relative power of the carrier, average power, and peak modulation are, respectively, 100, 128.6 and 141.8 units.

If the waves to be propagated are of short length, it becomes practical to dispose a plurality of dipoles along a vertical line as shown in Fig. 6. In this array the antennas are preferably half wave dipoles spaced about one half wave apart. 20 The center antenna 61 is fed by a transmission line 63 from a carrier current source 65. The upper side band may be supplied by the circuit arrangement of Fig. 1 and impressed on the upper dipole 67 through a transmission line 69 from a 25 source 71. The lower side band may be similarly supplied and impressed on the lower dipole 73 through a transmission line 75 from a source 77.

In the arrangement of Fig. 6 the power requirements are the same as the system of Fig. 2. The 30 carrier and sidebands establish circular fields about the vertical line through the antennas. The modulation factor will be the same at all points within the service area including points above and below the horizontal plane through the 35 center of the carrier wave.

Instead of supplying the upper sideband to the upper antenna and the lower sideband to the lower antenna, the sidebands may be supplied to both upper and lower antennas in accordance 40 with the system of Fig. 2. In this case for 100 units of carrier power, the average power for 100% modulation is 125 units, and the peak power is 45 150 units. The modulation factor will be uniformly 100% throughout a service area in a horizontal plane through the center of the center antenna but will decrease for planes above and below such service area.

Thus I have described an antenna circuit modulation system in which unmodulated carrier frequency currents are impressed on an antenna and radiated therefrom in a field of circular pattern. Modulation currents are impressed as upper and lower sidebands on other antennas suitably positioned with respect to the carrier frequency radiator. The sideband currents may be radiated as fields of circular, figure 8, or other patterns. A receiver within the service area combines the several currents which are amplified and demodulated in the conventional manner. Substantial 55 savings in power, and increased efficiency may be obtained by application of the foregoing systems. It should be understood that the actual apparatus and antenna arrays of my invention may follow numerous arrangements which will be obvious, in view of the foregoing description, to those skilled in the art.

I claim as my invention:

1. An antenna modulation system comprising a plurality of antennas, means for impressing an 75

unmodulated carrier current on one antenna, means for impressing an upper side band current on a second antenna, means for impressing a lower side band current on a third antenna, and 5 means for minimizing radiation coupling between said antennas.

2. An antenna modulation system comprising a plurality of antennas spaced at least .45 of a wave length from each other, means for impressing an 10 unmodulated carrier current on one of said antennas, means for impressing an upper sideband current on another of said antennas, and means for impressing a lower sideband current on a third of said antennas.

15 3. A transmission system including in combination a plurality of antennas, means for impressing in phase opposition upper and lower side band currents on a pair of said antennas, and means for impressing unmodulated carrier currents on a 20 third antenna of said plurality, said plurality of antennas being so constructed and arranged that substantially no carrier currents are induced in said pair of antennas, and substantially no sideband currents are induced in said third antenna.

25 4. A transmission system including in combination a plurality of antennas, means for impressing in phase opposition upper and lower side band currents on pairs of said antennas, and means for impressing unmodulated carrier currents on 30 a third antenna of said plurality, said plurality of antennas being so constructed and arranged that substantially no carrier currents are induced in said pairs of antennas, and substantially no sideband currents are induced in said third antenna.

35 5. An antenna modulation system comprising in combination a plurality of dipole antennas disposed substantially along a common line and spaced apart, means for impressing sideband frequency currents on two of said antennas, and 40 means for impressing unmodulated carrier frequency currents on one of said antennas positioned between said two antennas.

45 6. An antenna modulation system comprising in combination three half wave dipole antennas spaced a half wave length apart and disposed along a common vertical line, means for impressing unmodulated carrier frequency currents on

the centrally disposed one of said antennas, means for impressing currents of one sideband frequency on the upper of said antennas, and means for impressing currents of the other of said sideband frequency on the lower of said antennas.

7. An antenna modulation system comprising in combination three half wave dipole antennas spaced a half wave length apart and disposed along a common vertical line, means for impressing unmodulated carrier frequency currents 10 on the centrally disposed one of said antennas, and means for impressing currents of upper and lower sideband frequency in phase opposition on the upper and lower of said antennas.

8. The method of transmitting intelligence 15 which comprises radiating from an antenna an unmodulated carrier wave, radiating from a pair of antennas waves of upper and lower sideband frequency in phase opposition, and combining said waves at a point remote from the origin of 20 said radiation.

9. The method of transmitting intelligence which comprises radiating from a centrally disposed antenna an unmodulated carrier wave, 25 radiating from antennas on opposite sides of said centrally disposed antenna waves of upper and lower sideband frequency in phase opposition, preventing the interaction of said waves at their sources, and combining said waves at a point remote from the origin of said radiation. 30

10. The method of transmitting intelligence which comprises radiating from a centrally disposed radiator an unmodulated carrier wave, radiating from a plurality of sources disposed on opposite sides of said centrally disposed radiator 35 waves of upper and lower sideband frequency in phase opposition, and combining said waves at a point remote from the origin of said radiation.

11. The method of transmitting intelligence which comprises radiating an unmodulated carrier wave, radiating from a plurality of sources waves of upper and lower sideband frequency in phase opposition, preventing the interaction of said waves at their point of radiation, and combining said waves at a point remote from the origin of said radiation. 45

GEORGE H. BROWN.
